UNITED STATES PATENT OFFICE.

MIRIAM GROSS, OF MILWAUKEE, WISCONSIN, ASSIGNOR TO MIRIAM GROSS COMPANY, OF MILWAUKEE, WISCONSIN, A CORPORATION OF WISCONSIN.

DESIGN FOR A KNITTED DRESS.

Application filed October 19, 1927. Serial No. 23,806. Term of patent 3½ years.

To all whom it may concern:

Be it known that I, MIRIAM Gross, a citizen of the United States, residing at Milwaukee, in the county of Milwaukee and State of Wisconsin, have invented a new, original, and ornamental Design for Knitted Dresses, of which the following is a specification, reference being had to the accompanying drawing, forming part thereof.

The drawing is a front elevation of a knitted dress embodying the invention.

I claim:

The ornamental design for a knitted dress as shown.

MIRIAM GROSS.
